(57) CLAIM

The ornamental design for a chest, as shown and described.

DESCRIPTION

FIG. 1 is a left front perspective view of a bachelor's chest showing my new design; the top having been shown broken line boundary to indicate that the top forms no part of the claimed design. A similarly broken line boundary on the other figures has the same significance.

FIG. 2 is a side perspective view, the opposite side being a mirror image thereof;

FIG. 3 is a front perspective view thereof; and,

FIG. 4 is a top perspective view thereof.
